UNITED STATES PATENT OFFICE.

JOSEPH W. WHITE, OF CLEVELAND, OHIO, ASSIGNOR OF ONE-HALF TO
WASHINGTON S. TYLER, OF SAME PLACE.

WIRE-DRAWING APPARATUS

SPECIFICATION forming part of Letters Patent No. 431,499, dated July 1, 1890.

Application filed November 13, 1889. Serial No. 330,202. (No model.)

To all whom it may concern:

Be it known that I, JOSEPH W. WHITE, of Cleveland, in the county of Cuyahoga and State of Ohio, have invented certain new and useful Improvements in Wire-Drawing Apparatus; and I do hereby declare the following to be a full, clear, and exact description of the invention, such as will enable others skilled in the art to which it pertains to make and use the same.

My invention relates to improvements in wire-drawing apparatus; and it consists in certain features of construction and in combination of parts hereinafter described, and pointed out in the claims. In reducing, for instance, wire of medium size to the very small sizes suitable for bolting-cloth and various other purposes, the wire is drawn through a series of reducing-dies, and the motion of the wire being usually quite rapid, the friction between wire and dies is likely to generate so much heat that the dies are frequently injured thereby. More especially where diamond dies are used these are liable to be cracked and broken if they become heated to any considerable degree. I have therefore devised the mechanism illustrated in the accompanying drawings, in which the dies are constantly submerged in suitable lubricant.

Figure 1 is a plan. Fig. 2 is an elevation in section on line $x x$, Fig. 1. Fig. 3 is a corresponding elevation in section, showing a modification hereinafter described.

A represents a shallow vat for holding lubricant, the vat being constructed usually of cast-iron.

B and C are horizontal parallel shafts, the same extending into or over the line of the vat substantially as shown, these shafts outside the vat being intergeared in any suitable manner—for instance, as shown by means of engaging twin gears $m m$. One shaft is provided with a suitable driving-pulley—for instance, pulley N—and the one shaft is provided with a beveled gear O, that engages a bevel-gear P, the latter being mounted on the upright shaft p , on which shaft is also mounted the receiving or winding drum D. The transmitting mechanism, however, may be varied indefinitely, according to circumstances or to the judgment of the builder.

F is the reel on which the coil of wire is placed preparatory to drawing and from which the wire leads to one of the draft-drums B' C', these drums being mounted on the respective shafts B and C. The lower sections of drums B' C' extend well down into the vat, so that when the vat is partially filled with lubricant the lower section of these drums is submerged.

In Fig. 2 wire d from the reel is shown leading first around drum B' in the direction of the arrow, and from thence leading in the opposite direction around drum C', from whence it returns to drum B', and so on, the wire eventually leading to the receiving-drum D.

E are dies arranged in series, and for holding these dies in place are provided ribs $a a$, the same projecting upward from the bottom of the vat, these ribs having transverse slots for the passage of the wire. The dies are held in place against these ribs by the draft of the wire. One or more idle or guiding sheaves $l l$ are provided for guiding the wire onto the receiving-drum D. I will here remark that the relative position of drum D, as shown, is only for simplifying the gearing. Otherwise this drum may be placed in any desired position.

The vat A is kept supplied with suitable lubricant to cover the dies, and hence the dies, drums B' C', and the wire are kept comparatively cool. In case of diamond dies being employed the diamonds are set in a small metal disk, and it is these disks that engage ribs a , the disk and die proper being known to the trade as "die." The only object of rotating drums B' C' in opposite directions and crossing the wire, as shown in Fig. 2, is to be able to use two series of dies, both of which are submerged. In case fewer dies are needed, so that one series will be sufficient, drums B' C' may just as well be rotated in the same direction, in which case the wire would lead around the drums, as shown in Fig. 3. In such case gears $m m$ could be made smaller to make room for an intermediate gear, or the gearing could be arranged in any manner to accomplish the object.

What I claim is—

1. In a wire-drawing apparatus, the combination, with a vat for containing a lubricant,

horizontal shafts, draft-drums secured on said shafts and located within the vat, and reducing-dies located within the vat below the fluid-level and in position to engage the wire in its passage from one draft-drum to the other, of a reel on which the wire to be reduced is placed, and a winding-drum on which the reduced wire is wound, substantially as set forth.

10 2. In a wire-drawing apparatus, the combination, with a vat, horizontal shafts therein, draft-drums mounted on said shafts, and two

series of dies located within the vat below the fluid-level and between the draft-drums, of a reel on which the wire to be reduced is placed, and a winding-drum on which the reduced wire is wound, substantially as set forth. 15

In testimony whereof I sign this specification, in the presence of two witnesses, this 9th day of November, 1889.

JOSEPH W. WHITE.
